(57) **CLAIM**

The ornamental design for a face shield for use with eyewear frames, as shown and described.

DESCRIPTION

FIG. 1 is a front perspective view of a face mask shown in a used condition with a human figure in broken lines, showing my new design;

FIG. 2 is a front elevation view thereof;

FIG. 3 is a right side elevation view thereof;

FIG. 4 is a left side elevation view thereof;

FIG. 5 is a front perspective view of the design shown in FIG. 1 showing the face shield tilted upward; and,

FIG. 6 is a front perspective view of an alternative embodiment adapted for a sweat band and an additional elastic strap.

The broken line in FIGS. 1-6 showing of the eyeglass frame and the broken line showing of the human head depict the environment of the face shield mask and form no part thereof.

The broken line in FIG. 6 showing of the sweat band and elastic strap depict the environment of the face shield mask and form no part thereof.

The face shield mask shown in FIGS. 1-6 has a transparent or clear surface.
